UNITED STATES PATENT OFFICE.

FRANKLIN MESSINGER AND JOSEPH HENRY FULMER, OF NAZARETH,
PENNSYLVANIA.

DESIGN FOR A SNOW-GUARD FOR ROOFS.

SPECIFICATION forming part of Design No. 33,009, dated July 24, 1900.

Application filed June 4, 1900. Serial No. 19,078. Term of patent 3½ years.

To all whom it may concern:

Be it known that we, FRANKLIN MESSINGER and JOSEPH HENRY FULMER, citizens of the United States, residing at Nazareth, in the county of Northampton and State of Pennsylvania, have invented a new and original Design for a Snow-Guard for Roofs, of which the following is a specification.

This invention relates to a new and original design for a snow-guard for roofs; and the essential feature resides in a bird-form posed in upright position over an angular base having a flat extension, the form having the wings laterally projected and in vertical position, the contour of the lower body portion of the form being that of a sitting posture.

The accompanying drawing represents a perspective view of a snow-guard embodying the features of the design.

The numeral 1 designates the erect body of a bird, having the head portion 2 located between laterally-projected spread wings 3, the latter being vertically disposed and flat to the

front. The feet 4 of the body 1 depend over the upright member of a base having a right-²⁵ angular portion 5, the position of the bird on the said upright member of the base being that of a sitting posture, with the legs to the front. The right-angular portion 5 of the base has a flat bar 6 extending rearwardly ³⁰ therefrom at a slightly-upward angle and provided with a straight rear end at an angle to the plane of the bar, as at 7.

Having thus described the invention, what is claimed as new is—³⁵

The design for a snow-guard for roofs, herein shown and described.

In testimony that we claim the foregoing as our own we have hereto affixed our signatures in the presence of two witnesses.

FRANKLIN MESSINGER.
JOSEPH HENRY FULMER.
